FLEXIBLE PUMP PLUNGER

Charles S. Crickmer, Dallas, Tex., and Harvey R. Standlee, Tulsa, Okla., assignors to The Guiberson Corporation, Dallas, Tex., a corporation of Delaware

Application November 30, 1931, Serial No. 577,944

9 Claims. (Cl. 103—225)

This invention relates to new and useful improvements in flexible pump plungers.

The invention has particularly to do with plungers such as are usually connected to the end of a string of sucker rods in a well and which is reciprocated in the working barrel attached to the lower end of the well tubing, whereby the oil or other liquid is elevated.

One object of the invention is to provide an improved plunger which will be free from the usual non-metallic rings or cups, thus doing away with the quick wearing and cutting difficulty usually present in such structures.

A further object of the invention is to provide an improved pump plunger having an elongated expansion section arranged to be internally expanded so as to form a liquid-tight contact with the inner wall of the working barrel entirely around its circumference, whereby a more efficient lift is provided upon the upstroke of the plunger and a reduced frictional contact is had on the downstroke of said plunger.

A still further object of the invention is to provide an improved pump plunger having internally expansible longitudinal panels made integral at their ends with the body of the plunger and overlapping each other intermediate therein, so as to be free to expand and at the same time preventing leaks between their overlapping portions.

A construction designed to carry out the invention will be hereinafter described together with other features of the invention.

The invention will be more readily understood from a reading of the following specification and by reference to the accompanying drawings in which an example of the invention is shown, and wherein:

Figure 1 is an elevation of a plunger constructed in accordance with the invention,

Figure 2 is an enlarged plan view of the plunger,

Figure 3 is an enlarged horizontal cross-sectional view taken on the line 3—3 of Figure 1,

Figure 4 is an enlarged horizontal cross-sectional view taken on the line 4—4 of Figure 1,

Figure 5 is an enlarged horizontal cross-sectional view taken on the line 5—5 of Figure 1,

Figure 6 is an enlarged horizontal cross-sectional view taken on the line 6—6 of Figure 1,

Figure 7 is an enlarged horizontal cross-sectional view taken on the line 7—7 of Figure 1, and

Figure 8 is a vertical sectional view of the plunger.

In the drawings the numeral 10 designates an

elongated cylindrical hollow body having a screw-threaded pin 11 at its upper end. The upper end of the body is provided with a beveled shoulder 12 and a plurality of equally spaced vertical slots 13 forming outlets. In order to reinforce and strengthen the upper end of the body a central boss 14 extends downwardly from the pin 11 and is curved inwardly at the slots so as to give the latter sufficient area.

The body has its interior gradually increased in diameter downwardly from the boss 14 so that its wall is sufficiently reduced in thickness to provide the elongated elastic panels 15. Between the panels elongated openings are provided for receiving panels or slats 16 fastened therein. Each panel 15 has its vertical edges 17 beveled, and the vertical edges 18 of the arcuate panels 16 are undercut so as to overlie and contact with the edges 17. By this arrangement it will be seen, from an observation of Figure 6, that both the panels 15 and 16 may be expanded outwardly without breaking the contacts between the edges 17 and 18. This structure permits the intermediate or panel section of the plunger to be expanded and liquid-tight joints between the panels to be maintained.

Each panel 16 has its ends beveled at 19 and these bevels co-act with bevels 20 between the panels 15 to form grooves, in which a suitable welding or brazing metal 21 is introduced, when the panels 16 are brazed or welded to the body 10. The securing of the panels 16 at their ends leaves their edges 18 free and permits the forming of a liquid-tight contact between the edges 17 and 18. The metal 21 is finished off flush with the surface of the plunger body. External ring grooves 22 are formed in the body above and below the panels and split metallic rings 23 are seated in these grooves. These rings are sufficiently elastic to engage the inner wall of the working barrel (not shown) and thus prevent the passage of sand. By this arrangement sand will be prevented from engaging between the outer surfaces of the panels and the inner wall of the working barrel.

An integral cage or spider 24 is formed in the lower end of the body 10, as is best shown in Figures 6, 7 and 8. A bushing 25 is screwed into the lower end of the body and is counter-sunk to receive an annular valve seat 26. The seat is provided with an outwardly directed flange 27 held against a shoulder 28 by the bushing. A ball valve 29 rests upon the seat and is confined within the cage. By removing the bushing, the

seat and ball may be removed for any purpose found necessary.

The pin 11 is screwed into the socket A of a sucker rod B, whereby the plunger is supported and reciprocated by said rod. The plunger operates in the working barrel (not shown) in the usual manner. Upon the downstroke of the plunger the ball valve 29 is displaced upwardly in the cage 24 by the liquid, which thus rises in the body 10 and flows outward through the slots 13. Upon the upstroke of the plunger the valve is seated and the liquid trapped within the body 10 and above it. This liquid load will exert a lateral or internal pressure against the panels 15 and 16, which will thus be expanded so as to form a liquid-tight contact with the inner wall of the working barrel. The liquid thus being retained within and above the body 10 will be elevated upon the upstroke of the plunger. Upon the downstroke of the plunger the internal pressure will be relieved, thus permitting the panels to retract, and reducing their frictional contact with the wall of the working barrel during said downstroke. By fastening the panels at each end a more substantial structure is produced and danger of distorting the panels becomes very slight. If the upper ends of these panels were left free, they would be subject to distortion and might catch upon obstructions, or break off. Further, by securing both ends of the panels the greatest expansion will take place centrally between the ends, and only sufficient surface contact will be had to form the liquid-tight joint. Unless the expansion is restrained to some extent it would be too great and cause undue friction. By arranging the ball valve in the bottom of the body and eliminating relative movement between the panels and the sucker rod, a more simple device is provided, and there is little danger of battering. The sand rings are important as they not only tend to keep sand away from the panels, but also act to keep the inner surfaces of the working barrel free from obstructions. By making the barrel and panels as integral structure excessive wear and the danger of breaking parts is reduced to a minimum, particularly when compared with plungers wherein the panels are movable independently of the sucker rod and upper and lower portions of the plunger body.

Various changes in the size and shape of the different parts, as well as modifications and alterations, may be made within the scope of the appended claims.

Having illustrated and described a preferred form of the invention, what we claim, is:

1. In a pump plunger, a hollow body having longitudinal openings and longitudinal expansible panels between said openings and co-extensive therewith, and co-acting expansible panels secured at each end in said openings, the panels having overlapping edges in contact forming liquid-tight joints.
2. In a pump plunger, a hollow body having longitudinal openings and expansible panels between said openings and co-extensive therewith, the said panels of the body having beveled longitudinal edges, and co-acting expansible panels secured at each end in said openings and having undercut edges overlying and contacting with the edges of the first-named panels.

3. In a pump plunger, a hollow cylindrical body having a screw-threaded pin at its upper end and openings adjacent the pin for discharging liquid from the body, and longitudinal radially expandable panels secured fluid-tight at both their ends to the body and located below the openings thereof, said panels having their longitudinal edges in intimate contact.

4. In a pump plunger, a cylindrical hollow body having an opening at each end, longitudinal expansible panels intermediate the ends of the body, the body having elongated openings coextensive with the panel and beveled portions at each end of each opening, and separate elongated panels mounted in the openings of the body and having beveled ends co-acting with the beveled portions of the body to form recesses for receiving a fused metal for fastening the panels to the body.

5. A pump plunger comprising, an elongated hollow body having expandable fluid-tight elongated panels connected at each of their ends to the body having their longitudinal edges in intimate contact, whereby said panels expand intermediate their ends when subjected to internal fluid pressure.

6. A pump plunger comprising, an elongated hollow body having expandable fluid-tight elongated panels rigidly secured at each of their ends to the body having their longitudinal edges in intimate contact, whereby said panels expand intermediate their ends when subjected to internal fluid pressure.

7. A pump plunger comprising, an elongated hollow body having expandable fluid-tight elongated panels connected at each of their ends to the body having their longitudinal edges in intimate contact, whereby said panels expand intermediate their ends when subjected to internal fluid pressure, the longitudinal edges of the panels overlapping and contacting with each other, and means for attaching the body to a sucker rod.

8. A pump plunger comprising, an elongated hollow body having expandable fluid-tight elongated panels connected at each of their ends to the body having their longitudinal edges in intimate contact, whereby said panels expand intermediate their ends when subjected to internal fluid pressure, and sand rings mounted on the body above and below the upper and lower ends of the panels to prevent sand reaching the outer surfaces of the panels and entering therebetween.

9. A pump plunger comprising, an elongated hollow body having elongated longitudinal openings and elongated longitudinal expansible panels between said openings, elongated longitudinal expansible panels secured at each end in said openings of the body and having their longitudinal edges overlapping the longitudinal edges of the body panels so as to co-act therewith and form fluid-tight joints, and means for attaching the plunger to a pumping element, said plunger having fluid discharge openings above and below the panels, said panels being arranged to expand when subjected to internal fluid pressure.
